UNITED STATES PATENT OFFICE.

HERMAN BURCHESS, OF NEW YORK, N. Y.

BAG FRAME.

Application filed April 18, 1925. Serial No. 24,038.

This invention relates to travelling bag frames and in particular to the front and back frame piece construction to which the bag material is sewn.

5 A particular object of the invention is to provide frame pieces of such construction that the bag material may be easily sewn thereto. Heretofore in bag frames it has been the practice to make the frame pieces 10 from a plurality of parts joined by small bars to leave open spaces between the frame piece parts to which the bag material may be stitched, or the frame pieces have been provided with a plurality of openings which 15 had to be punched and through which the stitches could pass. A special construction of frame piece had to be provided to allow of either hand or machine stitching of the bag material, and this added materially to 20 the cost of the bag, and also hindered to a great extent the efficient sewing of the bag.

A further important object of my invention is to make a bag frame piece of a plurality of stiff or rigid parts having a joining penetrable intermediate strip to which 25 the bag material may be sewn.

Referring to the drawing wherein I have shown a preferred embodiment of my idea;

30 Figure 1 is a view in end elevation of a bag having therein a frame constructed in accordance with my invention,

Figure 2 is a view in side elevation of the bag illustrated in Figure 1,

35 Figure 3 is an enlarged cross section taken on the line 3—3 of Figure 2 and shows the frame structure and method of attaching the bag material thereto,

40 Figure 4 is an enlarged cross section through one of the frame pieces showing the construction thereof,

Figure 5 is a view similar to Figure 4 showing a modified form of construction of a frame piece,

45 Figure 6 is a view similar to Figure 4 showing a still further modified form of construction, and

Figure 7 is an enlarged side view of one 50 end of the frame pieces showing the method of attaching them together.

Referring to the drawing in detail 5 indicates a bag of the usual type, the body 6 of which is made of leather or other material having at its upper closing edges the steel frame pieces 7 and 8, the former being known in the trade and referred to herein 55 as the front frame piece and the latter as the

back frame piece; the back frame piece carrying the usual latches 9 and handle 10 while the front frame piece has attached thereto the latch engaging eyes 11, it being 60 understood that the frame pieces are pivoted together at their ends and the piece 7 fits snugly within piece 8 to form the closure for the bag.

In making up my frame pieces, both are 65 made in the same manner and it is thought that a description of one will suffice, and as shown in the drawing, particularly Figures 4 and 5, I employ two strips 12 and 13 of steel or other rigid metallic material which 70 I join by soldering or riveting thereto as at 14 the intermediate strip or binder 15 which is made of tin, copper or other easily penetratable metal, the same being formed to provide a step 16 therein. When the frame 75 piece is thus completed, it is japanned or covered with a thin leather as at 17. The edge 18 of the body 6 of the bag is then placed on the step 16 and is sewn directly to the penetratable metal intermediate strip 80 15 by using the heavy needle usually employed in the sewing of bag bodies to frame pieces. The stitches are indicated by numeral 19. This method of manufacturing 85 the frame allows for machine stitching and as no interference is offered to the needle the sewing is done neatly and without breaking the threads, while at the same time the result is a row of even stitching and a neat 90 appearance of the finished article.

In Figure 5 I have shown how the frame 95 piece may be made from a single piece of the penetrable metal by bending the ends thereof over as at 20 to stiffen the same, and soldering or pressing the turned over portion against the body of the piece. This method leaves the center 21 of the piece in one thickness to which the bag body can be readily 100 sewn, it being understood that the frame piece so made will first be japanned or covered with a layer of thin leather as before described.

In Figure 6 the frame pieces 12 and 13 are connected by the thin metal, the ends 22 and 23 of which are soldered or otherwise secured to the frame pieces and extend the width thereof. The binder in this instance can be placed on the exterior or interior of the frame pieces 12 and 13 while the intermediate portion of said binder is left free to receive the edge of the bag body as has been 110 described.

2 As seen in Figure 7 the ends of the frame parts are pivoted on the rivet 24 which passes therethrough and is covered by the thin leather covering 17. The ends of the frame parts may be cut square or rounded as desired.

It is evident therefore that I have provided a bag frame of new and novel construction and one to which the bag material can be sewn directly. Also in place of the thin metallic binder I may employ heavy fibre which can be riveted to the frame pieces. The joining of the frame parts by a strip of penetratable material provides a frame which can be made up at a reduced cost and one which will allow a bag to be made up neatly and with a minimum expenditure of time.

Having described my invention, what I claim is:

1. In a bag of the nature described, a bag frame member of comparatively soft material, a step on said frame member providing a stitching surface to which the bag material is adapted to be directly secured by a row of stitching, and a plurality of rein-

forcements integral with the stitching step.

2. In a bag of the nature described, a bag frame member of comparatively soft material, a top wall having a reinforcement integral therewith, a step of a single thickness of material integral with and depending from the top wall, said step providing a stitching surface to which the material of the bag is adapted to be directly secured by a row of stitching, and a wall bent back upon itself integral with and depending from said step.

3. In a bag of the nature described, a bag frame member of comparatively soft material, a step on said frame member providing a stitching surface to which the bag material is adapted to be directly secured by a row of stitching, the riser on said step adapted to act as an abutting surface for the edge of the bag material and a plurality of reinforcements integral with the stitching step, said reinforcements being formed by bending the stitching step back upon itself.

In testimony whereof I hereunto affix my signature.

HERMAN BURCHESS.
